US00D753057S

(12) **United States Design Patent**
Kubo et al.

(10) **Patent No.:** **US D753,057 S**
(b4) **Date of Patent:** **** Apr. 5, 2016**

(54) **CHARGING STATION FOR AN ELECTRONIC DEVICE FOR TRACKING PHYSICAL ACTIVITY**

(71) Applicant: **Omron Healthcare, Inc.**, Lake Forest, IL (US)

(72) Inventors: **Nobuo Kubo**, Buffalo Grove, IL (US); **Rodney Hal Monson**, Waukegan, IL (US); **Garrett Lee Winther**, Chicago, IL (US); **Ross Lockwood**, Chicago, IL (US); **Travis Schultz Lee**, Chicago, IL (US); **Shu Kuen Chang**, Evanston, IL (US); **Florian Maximilian Friedrich Gerlach**, Trofaich (AT)

(73) Assignee: **Omron Healthcare, Inc.**, Lake Forest, IL (US)

(**) Term: **14 Years**

(21) Appl. No.: **29/502,664**

(22) Filed: **Sep. 18, 2014**

(51) LOC (10) Cl. **13-02**

(52) U.S. Cl.

CLAIM

The ornamental design for a charging station for an electronic device for tracking physical activity, as shown and described.

DESCRIPTION

FIG. 1 is a top side perspective view of the charging station for an electronic device for tracking physical activity;

FIG. 2 is a front view thereof;

FIG. 3 is a rear view thereof;

FIG. 4 is a right side view thereof, with the left side being a mirror image;

FIG. 5 is a top view thereof; and,

FIG. 6 is a bottom view thereof.

The broken lines form no part of the claimed design and the drawings include surface shading that represents contour and not surface ornamentation.
